(57) **CLAIM**

The ornamental design for a tool for drawing, as shown and described.

DESCRIPTION

FIG. 1 is a perspective view of a tool for drawing showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear side perspective view thereof;

FIG. 9 is a detail view of area 9 shown in FIG. 2;

FIG. 10 is a detail view of area 10 shown in FIG. 2;

FIG. 11 is a detail view of area 11 shown in FIG. 2; and,

FIG. 12 is a detail view of area 12 shown in FIG. 2.

The broken lines represent the bounds of the detail views and form no part of the claim.
